FIG. 1

PATENTED JAN 5 1971

3,552,269

SHEET 2 OF 2

FIG. 2

HYDRAULICALLY OPERABLE LINEAR MOTOR

The present invention relates to a hydraulically operable linear motor with a piston which is reciprocable in the cylinder and has an annular surface connected to the piston rod continuously subjected to the working pressure of a fluid while the end surface of said piston is, by means of a hydraulically operable control valve, alternately subjected to the working pressure and the exhaust pressure.

The hydraulic actuation of the control valve is preferable over a mechanical actuation by cams, levers, or the like, especially at higher frequencies and when actuating impact masses, for instance, in connection with pile drivers, presses, and the like. Such hydraulic actuation, however, has certain drawbacks with the heretofore known designs according to which the reciprocating piston itself is provided with corresponding control edges and recesses. In this connection it may be mentioned that the working cylinder, in view of the required axial length of the piston, has to have at least twice the length of the piston stroke. This is particularly undesirable when a larger working stroke is necessary. Moreover, a change in the working stroke and thereby in the working frequency will not be possible with constant working pressure.

It is, therefore, an object of the present invention to overcome the above mentioned drawbacks.

It is another object of this invention to provide a hydraulically operable linear motor with reciprocating piston which will make it possible to design the working cylinder only slightly longer than the piston stroke, and which will also make it possible to vary the speed of the working frequency.

These and other objects and advantages of the invention will appear more clearly from the following specification in connection with the accompanying drawings, in which:

FIG. 1 shows a longitudinal section through a first embodiment of the present invention.

FIG. 2 represents a section through a modified embodiment of the invention which makes it possible to influence the working frequency by changing the piston stroke.

The hydraulically operable linear motor according to the present invention is characterized primarily in that the variable control pressure for actuating the control valve is formed in a conduit section which communicates with two annular grooves in the working cylinder which grooves are alternately covered up by the reciprocating piston, the conduit section also communicating with the exhaust line through a hydraulic throttle. With this arrangement, the working piston has no control edges or the like and consequently can be so short that the working cylinder is immaterially longer than the piston stroke.

In order to be able to vary the speed of the changes in the control pressure and thereby also the working frequency, the present invention provides that the cross sections of the throttles are variable. A change in the working stroke and thus in the working frequency is also possible, due to the fact that, according to a further development of the invention, the working cylinder in the vicinity of that end thereof which is alternately subjected to the pressure in the pressure line is provided not only with one annular groove but with a plurality of axially serially arranged annular grooves each of which is adapted selectively to be connected with the conduit section.

Referring now more specifically to the drawings, the working cylinder 1 of the linear motor has two working chambers 2 and 3 which are separated from each other by the piston 5 connected to the piston rod 4. The end face F_1 of the piston 5 delimits the working chamber 2 which through the feeding passage 6 and the control valve 7 is alternately connected to the pressure line 8 or the exhaust line 9, whereas the smaller annular surface F_2 , which surface F_2 is smaller than the surface F_1 by the cross section of the piston rod 4, delimits the working chamber 3.

If, as shown in FIGS. 1 and 2, the left-hand working chamber 2 communicates with the pressure line 8, piston 5 moves toward the right. If, however, the connection is established with the exhaust line 9, the piston moves toward the left. The necessary movement of the valve spool 10 in the

control valve 7 for effecting a control adjustment is effected hydraulically, for instance, in the following manner.

Through the intervention of one hydraulic throttle each 11, 12 and 13 a conduit section 14 communicates with two annular grooves 15 and 16 in the working cylinder 1 and with a passage 17 leading to the exhaust line 9. The control pressure p_{st} which builds up in this conduit section 14 acts upon the left-hand end face F_3 of the valve spool 10. The right-hand end face F_4 of the valve spool 10 which is somewhat less in cross section than the end face F_3 is continuously subjected to the working pressure p_o prevailing in the pressure line 8. The cylindrical inner chamber of the control valve 7 is in communication with three annular grooves 18, 19 and 20 which successively are connected with the exhaust line 9, the feeding passage 6 and the pressure line 8. The valve spool 10 also has an intermediate recess 21.

At a certain control pressure p_{st0} which is less than the working pressure p_o , the forces acting upon the surfaces F_3 and F_4 cancel each other out. When p_{st} increases, the valve spool 10 moves to the illustrated right-hand end position in which the left-hand working chamber 2 of the working cylinder is through the feeding passage 6, the annular groove 19, the recess 21, and the annular groove 20 in communication with the pressure line 8. With lower p_{st} , however, the valve spool 10 moves to its left-hand end position in which the working chamber 2 communicates through feeding passage 6, annular groove 19, recess 21, and annular groove 18 with the line 9. The change in the control pressure p_{st} is brought about when the reciprocating piston 5 in the working cylinder 1 covers the annular grooves 15 and 16 or relieves the same. The change in the control pressure p_{st} is, more specifically, brought about in the following manner.

As mentioned above, in the illustrated position, the left-hand working chamber 2 communicates with the pressure line 8. Thus, in both working chambers 2 and 3 the same pressure p_o prevails and since the surface F_1 is larger than the surface F_2 , the piston 5 moves toward the right. Moreover, in the conduit section 14, the maximum possible control pressure p_{st} is built up because the full-working pressure p_o acts upon both throttles 11 and 12.

As soon as with the piston movement toward the right the annular groove 16 is covered up by piston 5, the pressure p_o acts only upon the throttle 11. Consequently p_{st} decreases. When p_{st} drops below p_{st0} , the valve spool 10 moves to its left-hand end position in which the working chamber 2 and thus also the throttle 11 communicates with the exhaust line 9 so that the control pressure p_{st} drops still further. The piston will then, in view of the pressure p_o acting upon the annular surface F_2 move toward the left and while doing so frees first the annular groove 16 whereby p_{st} increases again but remains still below the value p_{st0} .

However, as soon as the piston 5 covers up the annular groove 15, the control pressure p_{st} increases again. When p_{st} exceeds p_{st0} , the valve spool 10 again moves to its right-hand end position, and the next piston stroke toward the right will start.

The reversal of the piston movement could be effected also only when the piston 5 during its leftward movement has completely moved beyond the annular groove 15 and the latter thereby is in communication with the right-hand working chamber 3 where the working pressure p_o continuously prevails. This depends primarily on the selection of the cross-sectional ratio $F_1:F_2$ and on the design of the hydraulic throttles 11, 12 and 13. If the cross sections of these throttles are variable, it is also possible to influence the difference ΔP_{st} between the maximum and minimum control pressure in the conduit section 14 and thereby the reversing period of the valve spool 10, in other words the working frequency of the linear motor.

FIG. 2 shows another possibility of influencing the working frequency, namely by changing the piston stroke. To this end, the annular groove 15 in the left-hand portion of the working cylinder 1 illustrated in FIG. 1 has been replaced by five axi-

ally serially arranged annular grooves 15a, 15b, 15c, 15d and 15e. Each of these annular grooves (in FIG. 2 the annular groove 15b) is adapted selectively to be connected with the hydraulic throttle 11 by opening the respective pertaining shut-off valve 22a, 22b, 22c, 22d, 22e and closing the remaining shut-off valves. The movement from one of these annular grooves to another one, which may also be interpreted as an axial displacement of the annular groove 15 in FIG. 1, brings about a corresponding change in the piston stroke and thereby in the working frequency.

The embodiment of FIG. 2 furthermore differs from that of FIG. 1 in that the control valve 7 for increasing the control impulse is, in the manner known per se, designed as servo valve which in its turn actuates the main control valve 7' with the main control spool 10', valve 7' being similar to valve 7 but having larger dimensions.

It is, of course, to be understood that the present invention is, by no means, limited to the particular embodiments shown in the drawings but also comprises any modifications within the scope of the appended claims.

I claim:

1. A hydraulically operable linear motor, which includes: a cylinder having first and second end walls respectively arranged at opposite ends of said cylinder, a double-acting piston reciprocally mounted in said cylinder, a piston rod extending through one of said cylinder end walls and being connected to one side of said piston so as to form on said one side an annular piston surface, first conduit means leading into said cylinder and continuously communicating with said annular piston surface for continuously conveying fluid pressure to said annular piston surface for continuously conveying fluid pressure to said annular piston surface when said first conduit means is connected to a source of fluid pressure, second conduit means continuously communicating with the other side of said piston, control valve means interposed between said first and second conduit means and movable to a first position to connect said second conduit means to said first conduit means and also movable to a second position to connect said second conduit means to an exhaust, said control valve means including first surface means in continuous communication with said first conduit means and fluid pressure operable to move said

control valve means to said second position, said control valve means also including second fluid operable surface means for moving said control valve means to said first position, and a fluid conveying control conduit system having first line means and second line means respectively leading into said cylinder on opposite sides of said piston when the latter is in a position intermediate its end positions, said control conduit system also having third line means communicating with said second fluid operable surface means and also having fourth line means communicating with said first and second and third line means and leading to an exhaust, and throttle means respectively arranged in said first and second and fourth line means.

2. A motor according to claim 1, in which said first surface means has a smaller surface area than said second surface means.

3. A motor according to claim 1, in which at least one of said throttle means is adjustable as to its through-flow-controlling cross section.

4. A motor according to claim 1, in which said cylinder at the regions where said first line means and said second line means lead into said cylinder is provided with annular grooves respectively communicating with said first and second line means.

5. A motor according to claim 1, in which said cylinder in the area where said first line means lead into said cylinder is provided with a plurality of circular grooves spaced from each other in the axial direction of said cylinder and adapted to be successively covered by said piston during the movement of the latter in one and the same direction and also adapted selectively to be placed into and out of fluid communication with said first line means.

6. A motor according to claim 5, which includes a plurality of adjustable throttle means associated with said circular grooves and said first line means adapted to communicate therewith.

7. A motor according to claim 1, which includes servovalve means associated with said control valve means for increasing the control impulses exerted upon the latter, said servovalve means being interposed between and in fluid communication with said first conduit means on one hand and said first and second line means on the other hand.
